UNITED STATES PATENT OFFICE.

JOHN LEON NEWHOUSE AND EMIL RUNKEL, OF PINE ISLAND, MINNESOTA.

BARBER'S FAN-SUPPORT AND THE LIKE.

1,103,816.

Specification of Letters Patent. Patented July 14, 1914.

Application filed April 4, 1913. Serial No. 758,991.

To all whom it may concern:

Be it known that we, JOHN LEON NEWHOUSE and EMIL RUNKEL, citizens of the United States, residing at Pine Island, in the county of Goodhue and State of Minnesota, have invented certain new and useful Improvements in Barbers' Fan-Supports and the like, of which the following is a specification.

- 10 This invention relates to certain improvements in fan supports; and the objects and nature of the invention will be readily understood by those skilled in the art in the light of the following explanation of the accompanying drawings illustrating what we now believe to be our preferred embodiment from among other formations, constructions and arrangements within the spirit and scope of the invention.
- 15 A particular object of the invention is to provide a spring drum, or the like, having a flexible connection wound thereon with an extended end to which any suitable fan is or can be attached, and a supporting device for the drum, adapted to be attached to the ceiling or other support and having a depending guide for said connection embodying a vertically adjustable guide and stop member arranged to engage the fan and limit 20 up its upward movement against the tension of the spring acting on the winding drum, so that the support can depend from the ceiling and normally maintain the fan within easy reach of a barber, for instance, 25 whereby the barber can reach the fan from his position beside his chair and pull the same down for use in fanning his customer, thereby unwinding the fan supporting connection from the drum and drawing the 30 same down through said guide, and whereby the fan when released by the barber will be automatically drawn back to normal position at the lower end of the guide and stop as the drum winds up said connection.
- 35 The invention consists in certain novel features in construction and in combinations and arrangements as more fully and particularly set forth and specified hereinafter.

Referring to the accompanying drawings:—Figure 1, is a perspective view, Fig. 2, is a sectional elevation. Figs. 3 and 4, are detail views.

In carrying our invention into effect we provide an elongated straight tubular bracket or guide 1, at its upper end carried by (and radially opening into the interior

of) an annular band or open end cylinder 2. This cylinder is provided with and supported by a wall plate or base 20, adapted to be fixedly secured to a ceiling or wall with the hereinbefore mentioned parts carried thereby and depending therefrom. An elongated sleeve or tube 3, is arranged and longitudinally adjustable in the member 1, and is secured in position projecting down 65 the desired distance from member 1, by clamping screw 4, adjustable radially through the lower end of member 1, into holding engagement with the surface of tube 3.

70 A spring actuated rotary winding drum 5, is removably arranged in the annular band 2, of the supporting bracket. This drum is mounted to revolve on a center pin or axis 6, arranged between removable heads 7 having 75 flanges fitting in the band 2, and closing the same and confining the winding drum in the band and between the heads. A flexible connection 8, is wound on said drum and has one end secured thereto while the free portion of the connection extends longitudinally through the depending tubular portion of the supporting bracket and through the adjustable tube 3, and at its lower extremity below the lower end of said tube 3, is secured to the handle of a fan 9 (or other suitable article) to support the same in an elevated position when not in use. The spring actuating the drum constantly tends 80 to rotate the drum in a direction to wind the 85 connection thereon and hold the fan against the lower end of the tube 3.

In the particular example illustrated, the drum is provided with a grooved or flanged periphery to receive the flexible connection, 95 while the drum is hollow to receive and inclose the drum rotating spring 10, having one end secured to the drum while the opposite end of the spring is secured or confined to the axis on which the drum rotates. For 100 instance, this axis can be longitudinally slotted or bifurcated to receive and confine the spring end and to permit removal of the drum and spring therefrom. In this particular example said axis is shown fixed to 105 and carried by one end head so that on the removal of the other end head, the drum can be slipped from said axis and from the annular band of the bracket for adjustment or repair of parts.

110 The device described is particularly intended to be secured to the ceiling of a bar-

ber shop or the like, to always maintain a fan out of the way and yet within convenient reach of the barber's position beside his chair so that when the fan is desired for drying a customer's face or hair, or other purposes, the barber can grasp the fan and draw the same down to position for use and can freely use the fan, even while attached to the flexible connection. When the barber is 10 through with the fan, he releases his hold thereon, and the spring drum will wind up the connection and pull the fan back to its normal position at the lower end of the adjustable guide and stop tube. This tube can 15 be adjusted vertically and secured to determine the elevation at which the fan will be normally held by the apparatus.

It is evident that various changes and modifications might be resorted to without 20 departing from the spirit and scope of our invention and hence we do not wish to limit ourselves to the exact disclosure hereof.

What we claim is;—

1. In combination, in a fan support, a 25 supporting bracket provided with an annular housing and with a rigid tubular member opening into and projecting from the housing, a removable head closing one end of the housing and provided with and carrying 30 a fixed drum shaft longitudinally slotted, a removable head closing the opposite end of the housing, a winding drum confined on said shaft by said heads, a drum actuating spring having one end removably 35 engaging said slot of the shaft, said drum having a flexible connection wound thereon with a free end extending through said tubular member and adapted to be attached to a fan, said tubular member provided with a 40 stop to limit the movement of the fan toward the drum, and means whereby said stop is adjustable longitudinally with respect to said member, substantially as described.
2. In combination, in a fan support, a 45 bracket provided with a winding drum housing having a removable head normally closing one end of the housing, a drum shaft arranged within the housing and fixed to the 50 opposite end head thereof, said shaft having a longitudinal slot opening through its

free end, a removable winding drum mounted on said shaft, and provided with an actuating spring having a portion removably entering said slot of the shaft, said drum having a flexible connection wound thereon with a free end adapted to have a fan secured thereto, and a flexible connection guide and fan stop projecting from and carried by said housing. 60

3. A fan support comprising a bracket adapted to be secured to a ceiling, or other support, and comprising a winding drum housing, a winding drum mounted in said housing, means supporting the same therein, 65 a tubular member projecting from and carried by said housing, a longitudinally-adjustable fan-stop tube arranged longitudinally of said tubular member, and means for securing said tube in the desired longitudinal adjustment with respect to said member, said drum adapted to carry a flexible connection extending therefrom freely through said member and tube and at its free end beyond said tube adapted to be 70 secured to a fan.

4. In combination, in a fan support, a supporting bracket provided with an annular housing and with a rigid tubular member opening into and projecting from the 80 housing, having a head closing one end of the housing and provided with and carrying a fixed drum shaft, a removable head closing the opposite end of the housing, a winding drum confined on said shaft by said 85 heads, a drum-actuating spring having one end removably coupled to the shaft, said drum having a flexible connection wound thereon with a free end extending through said tubular member and adapted to be attached to a fan, said tubular member provided with a stop to limit the movement of the fan toward the drum, and means whereby said stop is adjustable toward and from the drum, substantially as described. 90

In testimony whereof we affix our signatures in presence of two witnesses.

JOHN LEON NEWHOUSE.
EMIL RUNKEL.
